F. C. GORDON,
WEATHER STRIP,
FILED JUNE 21, 1921.

UNITED STATES PATENT OFFICE.

FREDERICK CHARLES GORDON, OF WESTFIELD, NEW JERSEY.

WEATHER STRIP.

Application filed June 21, 1921. Serial No. 479,323.

To all whom it may concern:

Be it known that I, FREDERICK CHARLES GORDON, a citizen of the United States, and a resident of Westfield, in the county of 5 Union and State of New Jersey, have invented a new and Improved Weather Strip, of which the following is a full, clear, and exact description.

This invention relates to weather strips 10 for use with windows and which may also be used with doors. Prior to this invention many types of weather strips were devised. The ordinary felt or rubber strip bears on the sash making it difficult to open the window and causing rapid wear of both sash and strip. During damp weather window sashes swell and if a rubber weather strip is used the sashes are likely to jam and are operated only with great difficulty, while in 15 dry weather when the sashes shrink the window is not tight enough to keep out the wind. Some strips are objectionable on account of the cost of installation; others are unsatisfactory under certain weather conditions, for instance, weather strips mounted 20 on the outside of windows often freeze together in winter and prevent the opening of the window; and many due to their construction continually get out of order during 25 use.

The object of this invention is the provision of a simple and durable weather strip that may be easily fitted on windows during the construction of the building, and that 35 may be readily mounted on the windows of any building after construction to make the windows practically airtight when closed but which permits them to open freely.

Another object is to provide a weather 40 strip that is not prominent and presents a good appearance.

These objects are accomplished by providing in conjunction with the lower window sash, a curved plate which engages with a 45 bevel face on the stool and serves to force the sash against the parting stop, and mounting a narrow curved plate on the upper sash which contacts with a projection in the window casing and forces the upper sash against 50 the parting stop, and means for drawing the lower portion of the upper sash against the upper portion of the lower sash.

These and other objects will be more clearly understood from the following detailed description and accompanying drawings.

Figure 1 is a plan view of the window showing the plate fixed to the lower sash;

Figure 2 is a vertical section of the window showing the weather strip in position; 60

Figure 3 shows the plate mounted on the sash and bearing on a bevel face cut on the window stool;

Figure 4 shows an end view of the spring, used in conjunction with the weather strip, 65 mounted on the upper sash;

Figure 5 is a side view of the spring that is mounted on the upper sash;

Figure 6 is a cross section on the line 6—6, 70 Figure 2, showing the means for drawing the sashes together;

Figure 7 is a cross section through the lower sash and stool, showing the curved plate in position and a strip with a bevel face mounted on the stool; and 75

Figure 8 shows a modification of the spring used as a weather strip.

Referring to the above-mentioned figures, a window casing 10 has a stool 11 and a sill 12. Mounted in the sides and top of the casing 10 are parting stops 13. Fitted into the casing and held in position by the stops are 80 two sashes, an upper sash 14 and a lower sash 15. Plates of glass 16 are fitted into the sashes and held in position by putty 17. 85

Fixed to the lower sash is a spring metal plate 18 which is preferably made of brass but may be made of some other flexible material. This plate is something the shape of the letter S with the upper portion straightened, and it is this upper portion that fits against the sash and is fastened thereto by means of nails or screws 19. The plate 18 extends across the window and bears against a bevel face 20 which may be cut in the stool 95 11 when the strip is being installed during the construction of the building.

The plate 18 is so located on the sash that the curved portion bears against the bevel face 20, thus forcing the sash against the 100 parting stop 13 when the window is closed. If the weather strip is to be applied to a window after the building has been constructed it is more satisfactory to supply a strip 21 which has a bevel face 22 and 105 mount this strip on the stool 11. The plate 18 is then so located on the lower sash that it bears against the bevel face 22 when the window is shut.

Mounted on the upper sash by means of 110 screws 24 is a plate 23 of similar cross section to the plate 18 but only a couple of

inches in length. This plate engages a screw 25 which is fixed in the upper part of the casing and serves to force the upper sash against the parting stop. A lock 26, 5 which may be of any ordinary type is provided to draw the upper part of the lower sash and the lower part of the upper sash together.

A modification of the spring plate 18 is 10 shown in Figure 8, in which case the upper straightened part of the S-shaped spring plate is bent to continue the lines of the upper part of the lower portion of the S, thus forming a spring plate a section of 15 which resembles a cane. In order to mount this spring plate on the window the straightened portion is driven into the sash and the curved portion co-operates with the bevel face on the stool to force the sash 20 into contact with the parting stop. A number of other modifications of this spring plate might be made. It is also possible to change the position of the spring plate and mount it on a stool so that it co-operates 25 with the window sash to force the sash into contact with the parting stop. In the case of the upper sash the narrow spring plate might be mounted on the window frame and the screw 25 fitted in the sash.

30 When the window is closed, the metal spring plate engages with the bevel face of the stool or on a strip fastened to the stool, and forces the sash against the parting stop. The spring plate on the upper sash 35 or frame engages with the screw or other projection and forces the upper sash against the parting stop. The lock mounted on the lower sash is then engaged with the catch on the upper sash and serves to draw the 40 upper and the lower sashes together thus forming a practically air-tight window which may be easily opened as soon as the lock is disengaged.

Claims:

45 1. In combination with a window comprising a casing, having parting stops mounted therein, and a plurality of window sashes, weather stripping of the class de-

scribed comprising a curved spring plate mounted on the lower sash and extending 50 across the same, a curved spring plate mounted on the upper sash, means associated with the window casing and co-operating with said curved spring plates to force the sashes against the parting stops, 55 and means in conjunction with the sashes for drawing them together when the window is closed.

2. In combination with a window comprising a casing including a stool, parting 60 stops and a pair of sashes slidably mounted in the casing, weather stripping of the class described comprising an S-shaped spring plate mounted on the lower sash and extending completely across the same, means 65 associated with the window casing presenting a bevel face to the spring plate co-operating with the same to force the lower end of the lower sash against the parting stops, an S-shaped spring plate mounted on the 70 upper sash, means provided in conjunction with the casing for engaging the S-shaped strip mounted on the upper sash to force the upper end of the sash against the parting stops, and means provided in conjunction 75 with the sashes for drawing their meeting rails together when the window is closed.

3. In combination with a window comprising a casing including a stool, parting 80 stops and sashes slidably mounted in said casing, weather stripping of the class described comprising an S-shaped spring metal plate mounted on the lower sash and extending across the window, means for mounting on the stool presenting a bevel 85 face to engage the spring metal plate to force said sash against the parting stops, a narrow S-shaped spring plate fixed to the upper sash, a projection attached to the casing and co-operating with said narrow S-shaped 90 spring plate to force the upper sash against the parting stops, and means mounted on the sashes for serving to draw their meeting rails together when the window is closed.

FREDERICK CHARLES GORDON.
